UNITED STATES PATENT OFFICE

EDWARD H. ANGIER, OF FRAMINGHAM, MASSACHUSETTS

BUILDING CONSTRUCTION

Original application filed April 27, 1931, Serial No. 533,156. Divided and this application filed February 19, 1932. Serial No. 594,031.

This invention relates to building structures and the object is to provide through the use of a novel material in the nature of building paper advantages both during and after 5 erection of the building as will hereinafter more fully appear. This application is a division of my application Serial No. 533,156, filed April 27, 1931, wherein the novel material utilized as a part of the structure is 10 claimed as such.

My invention will be well understood by reference to the following description taken in connection with the accompanying drawing showing an illustrative embodiment of 15 the invention and in which—

Fig. 1 is a fragmentary elevation of a wall with parts successively broken away;

Fig. 2 is a section on the line 2—2 of Fig. 1; and

Fig. 3 is an enlarged section through one of the elements used in the wall.

It will be understood that all the figures are more or less diagrammatic and do not show accurate proportions.

Referring to Fig. 1, I have there shown a portion of a wall embodying studs 5 arising from a sill 7. To the studs is secured as by means of the nails 9 a novel form of building paper 11, later to be described in detail. 20 Over the paper is placed the lathing 13, herein shown as a metal lathing, to which is applied a coating 15 of autosolidifying plastic such as plaster or stucco. Fig. 1 may be considered to represent an interior wall as 25 constructed in the colder parts of this country, or an exterior wall as constructed in some milder climates, as, for instance, southern California, where siding is dispensed with.

The paper 11 comprises an impermeable 30 body which is resiliently expansible and I have herein (see particularly Fig. 3) shown it as constructed of two craped sheets 17 and 19 of suitable paper such, for example, as thirty-pound kraft paper, connected by an 35 intervening film 21 of black asphalt or similar bituminous material. The sheets 17 and 19 are preferably also impregnated with this material, as indicated by the stippling in Fig. 3. Such material is substantially im-

of elastic expansibility due to the crapings. Means are provided for restraining the expansion of this body under moderate strains while permitting such expansion after greater strains occur. Herein I have shown 55 a sheet 23 of plain, substantially inextensible paper, say thirty-pound kraft, secured to one face of the craped duplex body layer as by means of asphalt 25 serving as an adhesive. While the complete sheet 11, as illustrated in 60 Fig. 3, may be used on the building structure shown in Fig. 1 either side out, I prefer to place the craped side next to the plaster to present a rough surface to aid in sustaining the wet plaster as it projects through the 65 openings in the lathing 13 when applied.

The material 11 may be handled during erection as an ordinary inextensible sheet. It will lie flat against the back of the lathing and back-support the plaster as it is applied 70 and will prevent the plaster from being forced through the interstices of the lathing in such manner that an excessive amount would be used. After erection of the building, however, and under the strains of use, 75 as, for example, if the building sinks, the plain sheet 23 may break, the bond by which it is attached to the craped body being ruptured, and the craped body will then be released to stretch to meet the strain without 80 breaking or ripping where the nails 9 are driven through, a defect of inexpensive building paper. Due to its elastic nature the craped body will meet without rupture a strain several times the breaking strain of 85 the plain sheet 23 and which would disrupt ordinary building paper as now commonly used and not having a substantial degree of resiliency.

I am aware that the invention may be embodied in other specific forms without departing from the spirit or essential attributes thereof, and I therefore desire the present embodiment to be considered in all respects as illustrative and not restrictive; reference 90 being had to the appended claims rather than to the foregoing description to indicate the scope of the invention.

I claim:

1. A building structure comprising a 100

50 permeable to moisture and has a wide range

frame, a resiliently expandable paper base sheet secured over the frame, a relatively frangible, substantially inextensible sheet likewise secured to the frame, a lathing over the sheets and autosolidified plastic on the lathing back-supported by said relatively frangible sheet.

2. A building structure comprising a frame, a resiliently expandable paper base sheet secured over the frame, relatively frangible means restraining the expansion thereof, a lathing over the sheet and autosolidified plastic on the lathing back-supported by said relatively frangible means.

15 15 In testimony whereof, I have signed my name to this specification.

EDWARD H. ANGIER.
